BERNARD ANSHER, Primary Examiner

FIG. 1 is a perspective view of a cell for X-ray spectroscopy, showing my new design;

FIG. 2 is a top plan view thereof;

FIG. 3 is a bottom plan view thereof;

FIG. 4 is a cross-section taken on line 4—4 of FIG. 2;

FIG. 5 is an exploded cross-section shown for clarity of illustration; and

FIG. 6 is a cross-section clearly depicting the relationship of the parts illustrated in FIGS. 1 and 4.

I claim:

The ornamental design for a cell for X-ray spectroscopy or similar article, substantially as shown and described.
